JAMES J. GILROY, OF KULPMONT, PENNSYLVANIA, ASSIGNOR OF ONE-HALF TO
FRANK S. WYDRA, OF KULPMONT, PENNSYLVANIA.

SAFETY DEVICE FOR WINDOW SASHES.

Application filed December 13, 1926. Serial No. 154,504.

This invention relates to a window fastener or safety device, and particularly to an attachment which will prevent a window sash from being opened to a greater distance than 5 a predetermined extent.

The primary object of the improved fastening means is to obstruct opening a window to such an extent as to permit ingress through the cleared open space and provide for ventilation and other airing advantages with safety, and preclude all possibility of manipulation of the attachment by unauthorized persons as to prevent manipulation of the parts of the attachment to increase the size 10 of the cleared opening, but readily controllable from the interior side of the sash by proper persons to effect a release which will permit free movement of the sash as may be desired.

20 A further object of the invention is to provide an attachment of the class specified capable of being easily applied in operative position with a minimum of expense of time, labor and cost of equipment.

25 With these and other objects and advantages in view, the invention consists in the preferred construction and arrangement of parts which will be more fully hereinafter described and claimed.

30 In the drawing:—

Figure 1, is a sectional side elevation of a part of a window sash and frame showing the improved fastener attachment applied thereto.

35 Figure 2, is an edge elevation of a portion of a window frame showing a part of the improved attachment applied thereto.

Figure 3, is an edge elevation of a portion of a window sash showing the remaining part 40 of the attachment applied thereto.

Figure 4, is a horizontal section on the line 4—4 of Figure 1.

Figure 5, is a longitudinal vertical section of the lock part of the improved attachment.

45 Figure 6, is a detail perspective view of the bolt forming part of the lock.

The improved attachment is shown with the lock part or member applied to the sash, and the striker plate attached to the window 50 frame at a suitable elevation, but it will be understood that these parts may be reversed, or, the lock member may be applied to the window frame and the striker plate to the sash. Moreover, the specific form of lock, 55 which will be hereinafter described, may be

modified and it will be understood that the invention is not limited to any specific form of lock so long as it embodies the essential part, which is a catch bolt hereinafter referred to as a preferred construction.

The essential parts of the improved attachment comprise a lock 5 and a striker plate 6, which as shown, are respectively applied to the window sash and window frame. The striker plate is of suitable thickness and is 60 inset in the window frame and held by suitable fastening devices 6^a, said striker plate being formed with a vertical slot 7 having an enlargement 8 at its lower extremity. The slot 7 with its lower enlarged extremity 8 is 65 applied over an elongated recess 7^a formed in the window frame. The sash, for convenience, is indicated by A and the frame by B, and do not have to be modified in their essential structural features to accommodate the 70 application of the improved fastener attachment.

The lock 5 comprises an enclosed casing 9 with a face flange 10 located adjacent to the outer edge of the sash A. The flange 10 extends above and below the upper and lower ends of the casing 9, as clearly shown by Fig. 5, and located in the upper part of the said casing 9 is a horizontal bolt 12, comprising a longitudinally extending guide member 14 80 and a lower catch member 15, which is shorter than the member 14 and has a depending shoulder 16 for engagement by the bit 16^a of a key 16^b, which is inserted in and withdrawn from the lock through the medium 85 of a suitable key hole as in ordinary structures of this class. The bolt 12 is normally forced outwardly by a spring 12^a, which bears at its outer extremity against a connecting web 17 between the outer ends of the members 14 and 15 and at its rear extremity 90 against the rear side of the lock casing 9. The members 14 and 15 are integrally formed with a head-plate 18 movable through an opening 13 in the outer side of the lock casing 9, the spring 12^a bearing against the said web 17. Extending outwardly from the head-plate 18 is a T-head 19, which is of such dimensions as to fit within the slot 7^a of the 95 striker plate 6, the lower enlarged extremity 8 of the said slot permitting the head 19 to be withdrawn therefrom. The lock casing 9 is set in a suitable mortise 20 formed in the window sash and held in applied position by fastening devices 21 inserted through the up- 100

105 8 of the said slot permitting the head 19 to be withdrawn therefrom. The lock casing 9 is set in a suitable mortise 20 formed in the window sash and held in applied position by fastening devices 21 inserted through the up- 110

per and lower extremities of the flange 10 of the said lock casing. The T-head 19 when projected by the spring 12^a remains in such projected position, and it is impossible to 5 separate the said T-head from the slot 7^a or its lower enlargement 8 after the key 16^b is withdrawn from the lock and held in possession of an authorized person, and hence the said T-head 19 will be in position continually to engage the slot 7 and its lower enlargement 8, and when the lock is thus set and the bolt 12 held in projected position the T-head 19 will slide or move in the slot 7. When the parts are properly assembled, as shown, 10 the T-portion 19^a of the head lies within the recess 7^a, and the neck 19^b of the said head 19 is free to slide in the slot 7 of the striker plate 6. The enlarged lower extremity 8 has upper inner converged walls 8^a, which remove any possibility of the head 19 catching 15 or being checked in its free action by projecting angular shoulders, and these inwardly inclined walls 8^a also serve as guides for centering the said head 19 relatively to the slot 20 7 of the striker plate.

When the sash A is regularly and operatively mounted in the frame B, the two essential parts of the attachment consisting of the lock 5 and striker plate 6, will be located 25 in close engaging relation, with the T-head 19 of the bolt 12 in the slot 7 of the plate 6 if the sash 8 is opened, or, with said T-head located in the lower enlarged extremity 8 of the slot 7 if the sash is closed. When the T-head 19 is in engagement with the slot 7 of the plate 6, the sash A may be moved vertically within the limits allowed by the attachment. When the bolt 12 is withdrawn so that the T-head 19 is disengaged from the plate 30 6 through the key 16^b by an authorized operator, the sash 8 may be freely moved upwardly and downwardly, or, a greater distance than permitted by the striker plate when normally engaged by the T-head, to thereby open 35 the sash a greater distance, or give a larger clearance.

When, however, the T-head 19 is in engagement with the striker plate 6, or, with the slot 7 and the lower enlarged extremity 8 of said slot, it is proposed to have a clearance opening of such dimensions as will prevent the entrance of a person, or unauthorized individual from the exterior side of the sash through the window frame, and any attempt 40 by an unauthorized person to tamper with the bolt 12 and disengage the T-head 19 from the striker plate will be defeated in view of the fact that it will be difficult to reach the key hole of the lock, and moreover, the form of key required will not be ordinarily understood or known to said unauthorized persons. It will also be very difficult to hold the T-head 19 disengaged from the striker plate 6 for the purpose of freely opening the sash 45 from the exterior side of the latter, and, as

a consequence the improved attachment embodying the essential features respectively carried by the sash and frame will serve as a safety means and obstruct opening or raising the sash a greater distance than that predetermined to give a minimized clearance or opening of such dimensions as to prevent entrance through a sash from the exterior of the window frame by an unauthorized person. Consequently, the window sash A can 50 be opened and left in open condition with safety for ventilating purposes and without liability of change of position when the T-head 19 of the bolt 12 is operatively associated with the slot 7 and lower enlarged extremity 8 of a plate 6.

It is proposed to use a key with a bit that will be of such form as will not ordinarily be accessible to an unauthorized person and it is obvious that other changes in view of the ordinary safety construction of locks generally may be adopted without in the least departing from the spirit of the invention.

What is claimed is:—

1. A safety attachment for a window sash and frame, comprising a flat plate for insertion in an elongated recess in one of said parts with one of its faces flush with the surface of the said part over the recess therein, said plate having an unbroken longitudinal slot narrower than the recess in which the plate is inserted and said slot being enlarged at its lower end, and a lock for attachment to the other part, said lock having a key operated bolt from which projects an outer locking T-head fitted and movable in said slot and recess and shaped to retain its association with the slot and recess until it is withdrawn from the lower enlargement of the slot by operation of the bolt, the lower portion of the body of the bolt having a depending key-engaging projection, the plate at the lower enlarged end of the slot being clear of structural projection and the T-head remaining in operative association with the plate until manually withdrawn.

2. A safety attachment for a window sash and frame, said attachment comprising a flat plate for insertion in an elongated recess in a side of one of said members with one of its faces flush with the surface of said part and adapted to be secured over said recess, said plate having an unbroken longitudinal slot therein with a lower terminal enlargement, and a lock for attachment to the other window part and having a key operated bolt from which projects an outer T-shaped locking head fitted and movable in said slot and withdrawable from the plate through the enlargement of the slot in the latter by manual retractile operation of the bolt, the lower portion of the bolt within its window part being provided with a lower depending rear key engageable projection, the upper portion of the side walls of the enlargement of the

slot converging toward the main portion of the slot to provide guide means and forming stop shoulders which restrict the withdrawal of the T-head until the latter reaches the 5 lower terminal larger portion of the enlargement.

3. A safety attachment for a window sash and frame, said attachment comprising a flat plate for insertion in a side recess in one 10 of the window parts flush with the surface of said part and adapted to be fixed over the said recess, the plate having an unbroken longitudinal slot therein with a lower terminal enlargement, and a lock having a casing for 15 insertion in a recess in the other window part and having an outer T-head projecting from

the center thereof and fitted and movable in said slot and shaped to retain association with the slot of said plate until the head is withdrawn from the lower enlargement of 20 said slot by operation of the bolt, the body of the bolt of the lock being longitudinally slotted to provide an upper guide member and a lower catch member spaced from the 25 guide member to engage a part of the lock casing and also engageable by a key, and a spring engaging in the slot between the guide and catch members.

In testimony whereof I have hereunto set my hand.

JAMES J. GILROY.
